UNITED STATES PATENT OFFICE.

LEONARD C. BAILEY, OF FLORENCE, COLORADO.

PICTURE-DISPLAY DEVICE.

No. 831,528.

Specification of Letters Patent.

Patented Sept. 25, 1906.

Application filed December 11, 1905. Serial No. 291,193.

To all whom it may concern:

Be it known that I, LEONARD C. BAILEY, a citizen of the United States, residing at Florence, in the county of Fremont and State of Colorado, have invented certain new and useful Improvements in Picture-Display Devices, of which the following is a specification:

This invention relates to a device for displaying objects, and especially pictures.

- o The especial purpose of the invention is to provide a picture-displaying device which can be very cheaply manufactured, which is adapted to display pictures of different sizes, which can be quickly and easily assembled and disassembled, and in which artistic and ornamental effects can be produced, thus contributing to the pleasure and instruction of the persons before whom the device is exhibited.
- o The essential features of the invention are capable of a wide range of treatment in their construction and arrangement, and in this application for patent I have shown only a preferred adaptation of the invention, with the understanding that various modifications may be applied thereto, all within the scope of my invention, as defined by the appended claims.

In the accompanying drawings, which form a part of this application, Figure 1 is a front elevation of one form of the device. Fig. 2 is a front elevation showing a slightly-modified form. Fig. 3 is a perspective view taken from a point above the device. Fig. 4 is a plan view of one of the members of the device hereinafter referred to as the "front" member. Fig. 5 is a plan view of another one of the members, hereinafter referred to as the "mat," "frame," or "partition." Fig. 6 is a plan view of the third member, which contributes to make up the device as a whole in its primary form, such member being termed the "side piece."

Referring to the drawings in detail, A A represent the side pieces of my improved exhibiting device, and same consists of pieces of cardboard or other suitable material cut in the rectangular form shown. In each of these pieces a short slot a' is cut, and parallel therewith and with each other are cut other slots a^2 , a^3 , and a^4 of different lengths, as shown in Fig. 6. Near the rear edge of the side pieces holes a^5 are formed for a purpose to be described.

B represents a piece of cardboard or other suitable material, preferably cut in the form

shown, in which there is a top portion having extended ends b' b'' , and between such extensions and the main body of the member B are notches b^2 b^3 , which are adapted to fit over 60 the side members when the parts are assembled. The member B is also formed with hook-shaped extensions b^3 on each side, which extensions are adapted to be fitted into the 65 slots a' and engage the members A at such points. The member B is cut away at its central portion to provide an opening b^4 , the edges of which can be on curved lines or given any fancy or artistic conformation that may 70 be desired. The upper portion of the member B, on which the extensions b' are formed, is adapted to have applied thereto ornamental designs or advertising matter, or the entire face of the member B can be designed or 75 ornamented as a proscenium-arch of a theater. As the members A and B are reversible, both sides can be utilized for ornamental or advertising purposes.

C, D, and E represent, respectively, frames 80 or mats of suitable material each provided with a central opening, as c' d' e' , said openings being of different sizes to accommodate different sizes of pictures or objects to be displayed therein or to be viewed therethrough. 85 The lower edge of each of the mats is notched, as shown at c^2 in Fig. 5. These mats are adapted to be slidably fitted in the openings a^2 a^3 a^4 , respectively, and the notches in the lower edges are adapted to engage the portions of the side members at the bottom of said openings, so as to hold the mats against lateral movement and also as a means of locking the two side members together. Through the holes a^5 in the opposite side 90 members may be strung a tape or other tying device, as a^6 , by which the rear edges of the side members may be flexibly, extensibly, and detachably connected together.

If desired, flaps F may be hinged to the 100 front piece B at each side of the opening b^4 , so as to form doors therefor, which may be opened or closed, as may be desired, such feature being indicated in Fig. 2 of the drawings. The portions of the side members 105 which project in front of the member B may be ornamented with pictures or representations of theater-boxes or may contain advertising matter, as may be desired. It will be apparent also that the faces of the mats C, 110 D, and E may contain pictures or portions of scenes correlated to each other, so as to make

2
in ensemble a picture having a perspective which is viewable through the openings in said mats and forming a suitable setting or frame for the pictures which may be in the background at the opening e' .

Instead of having a picture or pictures secured to the mats it is my design and purpose also to have the pictures movably applied thereto either by being slid vertically behind the mats or horizontally, as may be desired. When the pictures are inserted horizontally, they will be passed through the slots a^2 , a^3 , or a^4 , as may be desired, and where applied vertically the mats may be given any suitable construction at their rear side for such purpose. By having the portion of the side members in the rear of the front piece movable toward or away from each other through the tape a^6 it will be apparent that I provide more or less space between such sides for the display of pictures, thus accommodating the device to pictures of different widths. It will be apparent that the number of slots a^2 a^3 a^4 may be multiplied, so as to provide for a large number of mats or pictures and that the side members may extend rearwardly from the member B for a considerable distance and the mats C, D, and E used as partitions to mark off compartments bounded by the sides A and the mats, respectively, and in these compartments may be displayed devices other than pictures, the same appearing through the openings b^4 , c^4 , d^4 , and e^4 . When the device is not in use, the parts are all readily detachable, so that they can be placed flatwise and packed in small space, thus contributing to the convenience of shipment.

Having thus described my invention, what I claim is—

1. In a display device, side members, a front member having a display-opening and detachably secured to the side members and adapted to hold the side members in upright position, and means for displaying objects at the rear of the front member.
2. In a display device, side members extensibly secured together at one end, a front member, having a display-opening therein, means for detachably securing the front

member and the side members together, and means for supporting objects at the rear of said front member and between the side members.

3. In a display device, side members extensibly and detachably connected together at their rear ends, a front member adapted to detachably connect the side members together near their forward ends, said front member having a display-opening therein, means for displaying objects at the rear of the front member, said means comprising one or more mats detachably connected with the side members.

4. In a display device, side members having one or more slots therein and secured together at their rear ends, a front member connected with said side members and having a display-opening therein, and means for displaying pictures at the rear of said front member.

5. In a display device, side members having slots therein, a front member adapted to connect the side members together and hold them in upright position and having a display-opening therein, and means for connecting together the side members at the rear of said front member, whereby a plurality of communicating compartments are formed.

6. In a display device, side members connected together at their rear ends, a front member detachably connected to the side members and having a display-opening therein, and partitions adapted to connect together the side members and having display-openings therein.

7. In a display device, side members connected together at their rear ends, a front member detachably connected to the side members and having a display-opening therein, and means detachably connected with the side members whereby communicating compartments will be formed at the rear of the front member.

In testimony whereof I affix my signature in presence of two witnesses.

LEONARD C. BAILEY.
